UNITED STATES PATENT OFFICE.

HARVY EVERETT, OF LEWISTON, IDAHO.

SIGN.

1,077,514.

Specification of Letters Patent.

Patented Nov. 4, 1913.

Application filed December 18, 1912. Serial No. 737,520.

To all whom it may concern:

Be it known that I, HARVY EVERETT, a citizen of the United States, residing at Lewiston, in the county of Nez Perce and 5 State of Idaho, have invented certain new and useful Improvements in Signs, of which the following is a specification, reference being had to the accompanying drawings.

This invention relates to new and useful 10 improvements in signs, and an object thereof is the provision of a sign comprising a supporting member and sign letters which may be easily and quickly attached to or detached from the supporting member.

15 Another object of the invention is the provision of a sign comprising vertical standards having transversely extending wires connected thereto, the wires being arranged in pairs and sign letters having 20 hooks connected thereto at their upper and lower ends, the hooks being adapted for engagement with the transversely extending wires.

A further object of this invention is the 25 provision of a sign comprising vertical standards and pairs of wires extending transversely between said standards, and means connected to one wire of each pair whereby the wire may be loosened and tightened 30 so that sign letters having hooks at their opposite ends may be secured to the transversely extending pairs of wires.

With these and other objects in view, my 35 invention consists in certain novel constructions, combinations, and arrangements of parts, to be hereinafter more fully described, claimed, and illustrated in the accompanying drawing, in which:

Figure 1 is a front elevation of my 40 device. Fig. 2 is a front elevation of one end of one pair of the wires showing the standard in section. Fig. 3 is a section taken on line 3—3 of Fig. 1. Fig. 4 is a view similar to Fig. 3 showing the position of the 45 wire 6^b when loosened in dotted lines. Fig. 5 is a fragmentary end view of one of the standards showing one of the adjustable

pins, and Fig. 6 is a section taken on the line 6—6 of Fig. 1.

Referring more particularly to the drawing, the numeral 1 designates a base plate having vertical standards 2 secured thereto, the standards being maintained in upright position by suitable braces 3. The standards are formed with a vertical series of openings 4, the openings being arranged in pairs and the upper opening of each pair being threaded as at 5. Transversely extending wires 6 are arranged between the standards 2, each of the wires being rigidly connected at one end to one of standards as at 7. The wires 6 are arranged in pairs, and the lower wires 6^a of the pairs are rigidly secured to the other standard as at 8, and the upper wire 6^b of each pair has a threaded stem or pin 9 secured to its extremity, the pins 9 being adapted for adjustable engagement in the threaded openings 5. The letters 10 are formed on their upper and lower ends with inwardly extending hooks 11 which are 70 adapted to engage one pair of wires 6 of the sign. It will be seen that when it is desired to attach the letters to the supporting member of the sign, it is only necessary to turn the threaded pin or stem 9 of one pair of 75 wires to loosen the wire 6^b whereupon the hooks 11 may be engaged with the wires and the pin can be rotated to tighten the wire 6^b whereupon the letter will be maintained in position.

80 From the above description taken in connection with the accompanying drawing, it will be seen that I have provided a sign in which the letters thereof are readily interchangeable, and one in which the letters may 85 be quickly applied to or removed from the wires of the sign.

Having thus fully described my invention, what I desire to claim and secure by Letters Patent is:—

90 A sign comprising a pair of supports, a pair of wires extending between said supports, one end of each of said wires being rigidly secured to one of said supports, one

of said wires being rigidly secured at its opposite end to the other of said supports, said other support being formed with a transversely extending threaded opening, a longitudinally extending threaded pin engaged in said opening and projecting beyond the opposite sides of said support, the opposite end of the other of said wires being secured to the inner end of said pin,

said pin being adjustable in said opening to tighten and loosen said other wire, as and for the purpose described.

In testimony whereof I hereunto affix my signature in the presence of two witnesses.

HARVY EVERETT.

Witnesses:

C. A. M. BOLES,
H. H. BOCKRIUS.
